UNITED STATES PATENT OFFICE.

RICHARD P. BROWN, OF PHILADELPHIA, PENNSYLVANIA, ASSIGNOR TO THE BROWN INSTRUMENT COMPANY, OF PHILADELPHIA, PENNSYLVANIA, A CORPORATION OF PENNSYLVANIA.

SAFETY DEVICE FOR PYROMETERS.

Application filed February 20, 1922. Serial No. 538,114.

To all whom it may concern:

Be it known that I, RICHARD P. BROWN, a citizen of the United States, and a resident of Philadelphia, county of Philadelphia, 5 State of Pennsylvania, have invented a certain new and useful Improvement in Safety Devices for Pyrometers, of which the following is a specification.

Some of the objects of the present invention are to provide a safety control means for pyrometers, thermo-couples, furnace control devices, gas, liquid and vapor actuated instruments, or any other instrument wherein operation beyond a predetermined limit may 10 result in a condition of danger; to provide an alarm system for indicating recording, and any other instruments; to provide means to prevent a heating unit from over-heating in case the controlling device ceases to function; to provide an emergency control for 15 heating units arranged to operate automatically if the thermo-couple circuit of the heating unit becomes inoperative; to provide means for automatically cutting out or shutting down a heating unit under excess temperature conditions; to provide means for rendering a safety device for a heating unit 20 ineffective under certain conditions; and to provide other improvements as will herein- 25 after appear.

In the accompanying drawings, Fig. 1 represents a detail, in plan, of a measuring instrument equipped with one form of the present invention; Fig. 2 represents a front 30 elevation of the same; Fig. 3 represents a diagram of a pyrometric system embodying the present invention; and Fig. 4 represents a diagram of another form of the invention.

Referring to the drawings, one form of 35 the present invention is shown as applied to a pyrometric system including an electrical measuring instrument 10, here shown as of the recording type employing means for automatically controlling the temperature of a 40 furnace or other heating unit at a distant point. The control mechanism shown for purposes of illustration is that fully described in a co-pending application Serial No. 492,937, and may be here briefly described 45 as a contact control comprising a contact member 11 arranged to be adjustably carried by a cross-piece 12 which is fixed to a movable pivoted bar 13, generally known as the depression bar. The bar 13 in the present construction, is provided with a slot 14, through

which pass fastening studs or screws 15 by which the contact member 11 is locked in its adjusted position. This contact member 11 carries a contactor 16 arranged to control a heating unit to increase the temperature thereof, and a contactor 17 arranged to control a heating unit to decrease the temperature thereof, both of said contactors 16 and 17 being positioned to engage a common contact 18. The contactors 16 and 17 are arranged to be selectively actuated by the index or pointer 20 of the instrument 10 as the depressor bar 13 functions. It will be understood that the contact member 11 is fixed in a position on the instrument 10 corresponding to the predetermined constant temperature desired to be maintained, the contactor 16 being on the low side and the contactor 17 being on the high side of the desired temperature. 75

A thermo-couple 21 of any well known form is located at a furnace 22 or in any other heat zone to be controlled and has leads 23 and 24 connected to the instrument 10 to actuate the sensitive element thereof in the usual manner to cause the pointer 20 to move to a position corresponding to the furnace or zone temperature. 80

For controlling the temperature of the furnace 22 an electric heating unit 25 is provided one terminal of which is connected by a conductor 26 to one side of the service line or source of current while the other terminal thereof is connected by a conductor 27 to a movable circuit closer arm 28 of an automatic control switch 30. The arm 28 is pivotally mounted to move to open position by gravity and to be closed by the magnetic action of a relay coil 31, bringing it into engagement with the contact 32 which is connected to the opposite side of the service line. 85

The relay coil 31 is arranged to be energized and deenergized by two circuits including respectively the contactors 16 and 17, and having a common return through the contact 18. The low temperature circuit, which is the one to energize the coil 31 to cause the unit 25 to heat the furnace, comprises the contactor 16, a conductor 33 leading to the low binding post L, conductor 34 to one side of the service line, then across the line to a conductor 35, to coil 31, to conductor 36 to binding post C and a conductor 37 to common contact 18. 100

The high temperature circuit comprises 105

the contactor 17, a conductor 38, to binding post H, conductor 40 to one side of service line, across the line to conductor 41, a resistance 42 and the conductor 36 to binding post 5 C to the common contact 18. The contact 32 is connected to the conductor 35, so that, when the arm 28 contacts therewith, current will flow to the heating unit 25.

As fully explained in the above mentioned 10 copending application, the circuits including the contactors 16 and 17 may be arranged to also operate signal lights or other alarm devices to give notice of danger or limit temperature.

15 It will be apparent from the foregoing that the functioning of the instrument pointer 20, by which the control circuits are selected, is dependent upon the proper functioning of the thermo-couple 21 and its circuit, so that should it cease to operate there would be no further control of the heat unit 25. Thus, if the circuit of the thermo-couple 21 should break, or the thermo-couple 21 become inoperative while the heating 25 unit 25 was heating, the pointer 20 would at once return to its zero position, and in consequence when the temperature reached the predetermined limit there would be nothing to cut off the heating unit 25 and the temperature would continue to rise.

For the purpose of automatically cutting out or shutting down the heating unit in the event above referred to, namely the failure of the thermo-couple circuit to function, an 35 auxiliary or safety circuit is provided including a conductor 43, contactor 44, contact 45 and conductor 46, the two conductors 43 and 46 being respectively connected to the binding posts C and H, so that this auxiliary 40 circuit is connected in multiple with the high temperature circuit, which when closed deenergizes the relay coil 31. The contactor 44 and contacts 45 are suitably mounted within the casing of the instrument 10 in a 45 position to locate the contactor 44 in the path of movement of the pointer 20, when the latter is in its zero position, so that the action of the depressor bar 13 is to cause the pointer 20 to shift the contactor 44 into engagement with the contact 45 to thereby 50 close the control circuit which deenergizes the coil 31. This circuit is from contact 45, conductor 46, binding post H, conductor 40, across service line to conductor 41, resistance 55 42, conductor 36 to binding post C, conductor 43 to contactor 44. The closing of this circuit short circuits the coil 31 so that the switch arm 28 returns by gravity to its open circuit position and thus breaks the 60 heating unit circuit so that there is no further increase in temperature. Of course, when the depressor bar 13 rises the contactor 44 breaks contact with contact 45 and the short circuit around the coil 31 is broken and 65 the current again flows from the service

line through the coil 31, but the magnetic pull under this condition is not sufficient to actuate the switch arm 28 because of the resistance 42 now in series with the coil 31.

In the foregoing emergency or safety system 70 it will be noted that the pointer 20 is in its zero or initial position when the safety contacts are caused to function, and since the pointer 20 is also in this zero position at starting time under normal conditions, it is 75 desirable to provide a means to prevent the emergency circuit from functioning, as otherwise there would be no heating of the furnace at all. To that end one means for accomplishing this result consists of a spring 80 arm 47 fixed at one end to the casing of the instrument 10 and having a free end in close proximity to the normal zero position of the pointer 20, and arranged to engage the said pointer 20. A feed screw 48 is threaded 85 through the casing 10 into position to engage the arm 47 so that when fed inwardly it will move the arm 47 to shift the pointer 20 manually out of alignment with the contactor 44. When this is accomplished the 90 system may be started and as the pointer 20 cannot engage the contactor 44, the heating unit functions under the control of the instrument as long as the thermo-couple circuit is operative. As soon as the system has 95 operated sufficiently to retain the pointer 20 beyond the contactor 44, the screw 48 is backed off to its normal position, and thereby releases the spring arm 47 which then returns to a position where it will not interfere with the pointer 20 should the latter return to its normal zero point. Now, if the 100 thermo-couple 21 ceases to function or there is a break in its circuit, the pointer 20 immediately swings back to the initial position 105 above the contactor 44 and consequently the next operation of the depressor bar 13 moves the pointer 20 to close the safety circuit through the contactor 44 and contact 45. As a result the line current short circuits the 110 coil 31 by traversing conductor 36 to binding post C, and thence by contactor 44 and contact 45 to the line. This releases the switch arm 28 so that the circuit of the heating unit is broken and no further rise in temperature 115 can take place.

In order that notice may be given that the heating unit has shut down, and thus prevent the furnace from cooling down too much, it is preferable to connect an alarm 120 signal 49 into the emergency circuit, for example, connecting a bell or a lamp with the conductor 46 so that an attendant may be promptly advised of the changed condition of the system.

125 In the form of the invention shown in Fig. 4, a suitable electrically operated switch 50 is arranged to control the opening and closing of a circuit 51 which is arranged to operate an electric furnace, a valve, 130

or any other electrically controlled device. The operative and inoperative positions of the switch 50 are normally controlled respectively by a circuit L including a contact 52 and a contactor 53 and a circuit H including a contact 54 and a contactor 55, the circuit L, when closed, serving to operate the switch 50 to energize the circuit 51, and the circuit H, when closed, serving to operate the switch 50 to deenergize the circuit 51. The selection of the circuits is determined in the present instance by the instrument pointer 20 as heretofore explained. Suitable conductors 56 and 57 bring current from the service line to the switch 50.

For the purpose of deenergizing the operating circuit 51, in case the circuit of the measuring instrument is broken, a rocker arm 60 is provided and pivoted at 61 just below the zero position of the pointer 20. This arm 60 carries two contactors 62 and 63 arranged at opposite sides of the pivot 61, one of which 62 is located to be actuated by the pointer 20 when it is in the zero position, while the other 63 is somewhat removed therefrom on the high side of the instrument scale. Trip members 64 and 65 project from the respective ends of the arm 60 so that one or the other is in the path of movement of the pointer 20 according to the tilted position of the arm 60. A spring 66 may be provided, if desired, to accelerate the tilting movement of the arm 60 when struck by the pointer 20. The arm 60 is connected by a conductor 67 to one side of the service line, so that the arm 60 becomes a selecting means for two control circuits. One of these circuits includes a contact 70, arranged to be engaged by the contactor 62, a conductor 71, a spring arm 73 and either a connection 74 with the circuit L or a connection 75 with the circuit H. The other of these circuits includes a contact 76, arranged to be engaged by the contactor 63, a solenoid coil 77 and a conductor 78 to the other side of the service line. The selection of the circuit L or circuit H by the spring arm 73 is determined by a projection 80 from the core 81 of the solenoid 77 and two contactors 82 and 83 fixed to the spring arm 73 and arranged respectively to engage contacts 84 and 85, the former being in the circuit L and the latter in the circuit H. When the solenoid 77 is deenergized the projection 80 rests upon the arm 73 to break the contact between the contactor 83 and the contact 85 while making the contact between the contactor 82 and the contact 84. This is the condition of the system at starting times so that the circuit L is closed to cause the switch 50 to energize the controlled device. When the system is in operation it is necessary to maintain the safety portion of the circuit L open and for this purpose a second solenoid 86 is provided having a keeper

87, carried by its core, which abuts an extension 88 on the upper end of the core 81. A latch notch 90 is formed in the extension 88 so arranged that, when the solenoid 77 is energized, it will be engaged by the keeper 87. The solenoid 86 is connected directly to the service line so that it is energized at all times when the main current is on.

The operation of this form of the invention is as follows: In Fig. 4 the parts are in starting position and consequently the control switch 50 is energized by the circuit L as soon as the current is turned on. As soon as the measuring instrument responds to current the pointer 20 moves to the right as seen in Fig. 4, and thereby, either under the action of the depressor bar 13 or by striking the trip member 65, causes the arm 60 to tilt, thereby breaking contact between contactor 62 and the contact 70, and making contact between the contactor 63 and the contact 76. This closes the circuit through the solenoid 77 and causes the core 81 to lift out of engagement with the spring arm 73 and its latch 90 to be engaged by the keeper 87 and thus thereafter be held elevated while the system is in operation. The spring arm 73, being free, breaks the circuit of contactor 82 and contact 84 but brings the contactor 83 into engagement with the contact 85. This leaves the safety circuit H open only between the contactor 62 and the contact 70. The system can now operate continuously in the required manner. If, however, the instrument circuit should become broken through accident or otherwise, the pointer 20 immediately brings back to zero position, thereby striking the rocker arm 60 and causing it to shift to break the circuit of contactor 63 and the contact 76 but closing contact between the contactor 62 and the contact 70 which closes the safety circuit H to cause the control switch 50 to break the operating circuit 51 and thus shut down the heating unit or other controlled device to prevent overheating or operation beyond the intended limit.

Although only two forms are shown in which this invention may be embodied, it is to be understood that the invention is not limited to any specific construction, but might be applied in various forms without departing from the spirit of the invention or the scope of the appended claims.

Having thus described my invention, I claim:

1. In an electrical system, a heating unit, a pyrometer arranged to control said heating unit, and means rendered operative by an inoperative condition of said pyrometer for causing said heating unit to be shut down.

2. In an electrical system, a heating unit, a measuring instrument, a thermo-couple controlled by said heating unit and control-

- ling said instrument, and means for automatically shutting down said heating unit in case said thermo-couple ceases to control said instrument.
5. 3. In an electrical system, a heating unit, a measuring instrument provided with a pointer, means controlled by the temperature of said heating unit for operating said measuring instrument, and emergency means located adjacent the normal zero of said instrument and controlled by said pointer for shutting down said heating unit under abnormal conditions.
4. In an electrical system, a heating unit, a measuring instrument provided with a pointer, means controlled by the temperature of said heating unit for operating said measuring instrument, emergency means located adjacent the normal zero of said instrument and controlled by said pointer for shutting down said heating unit under abnormal conditions, and means for rendering said emergency means inoperative under starting conditions.
25. 5. In an electrical system, a heating unit, a measuring instrument provided with a pointer, means controlled by the temperature of said heating unit for operating said measuring instrument, emergency means located adjacent the normal zero of said instrument and controlled by said pointer for shutting down said heating unit under abnormal conditions, and means including a pointer shifting device for rendering said emergency means inoperative under starting conditions.
6. In an electrical system, the combination of an electrical instrument, an actuating circuit for said instrument, a device to be operated, a circuit for controlling said device, and means actuated by the failure of said actuating circuit to function and operating through said control circuit to render said device inoperative.
45. 7. In an electrical system, the combination of an electrical instrument, an actuating circuit for said instrument, a device to be operated, a circuit controlled by said instrument for controlling said device, and means actuated by the failure of said actuating circuit to function and operating through said control circuit to render said device inoperative.
8. In an electrical system, a device to be operated, a circuit for controlling said device, a measuring instrument provided with a pointer and arranged to control said circuit, an actuating circuit for said instrument, and means controlled by said pointer when said actuating circuit is broken and operating through said control circuit for rendering said device inoperative.
9. In an electrical system, a device to be operated, a circuit for controlling said device, a measuring instrument provided with a pointer and arranged to control said circuit, an actuating circuit for said instrument, and safety means including a switch operated by said pointer when returned to zero position by a break in said actuating circuit for rendering said device inoperative.
10. In an electrical system, a device to be operated, a circuit for controlling said device, a measuring instrument provided with a pointer and arranged to control said circuit, an actuating circuit for said instrument, safety means including a switch operated by said pointer when returned to zero position by a break in said actuating circuit for rendering said device inoperative, and means for rendering said safety means ineffective under starting conditions.
11. In an electrical system, a device to be operated, a circuit for controlling said device, a measuring instrument provided with a pointer and arranged to control said circuit, an actuating circuit for said instrument, safety means including a switch operated by said pointer when returned to zero position by a break in said actuating circuit for rendering said device inoperative, and means including a solenoid controlled switch for connecting said safety means to said control circuit.

Signed at Philadelphia, in the county of Philadelphia and State of Pennsylvania, this 7 day of February, 1922.

RICHARD P. BROWN.
